**METHOD OF OPERATING A VERTICAL
VENETIAN BLIND**
Andrew J. Toti, 311 W. River Road,
Modesto, Calif. 95351
Filed Aug. 13, 1965, Ser. No. 479,531
5 Claims. (Cl. 160—174)

This invention relates to a Venetian blind construction in which the blind slats are vertically arranged. More particularly, this invention relates to a traverse type vertical Venetian blind construction to be mounted in a window or like opening in a building for traverse movement therein between a folded or retracted position, in which the blind slats are gathered together in a compact pack so that the window or like opening is unobstructed thereby, and an extended position, in which the slats are unfolded and extend across the window or like opening.

Still more particularly, this invention relates to traverse type vertical Venetian blind in which the blind slats, when in an extended position, are located in a preselected angular orientation relative to a reference axis or plane, which orientation is selected at the time the slats are in a retracted position. The Venetian blind of this invention includes as an important part thereof simple means for automatically and uniformly positioning the respective slats in a preselected one of several predetermined angular orientations when said slats are traversed from a retracted position toward an extended position.

In this regard, the series of slats which make up the blind of this invention are responsive to the angular orientation imparted to a first slat of the series when the slat series is in the retracted position. That is, the orientation of the first slat of the series determines the manner in which the slat positioning means of the blind actuates the other slats of the series and the angular orientation imparted thereto when the slats are traversed to an extended position. In this connection, this invention further relates to a method of traversing a series of slats of a vertical Venetian blind by actuating a first slat of the series and thereby automatically positioning the other slats in a preselected angular orientation corresponding to the angular orientation imparted to the first slat when the slat series is in a retracted position.

The present invention may be embodied in a traverse type vertical Venetian blind employing only one series of slats, or more than one series of slats, positionable adjacent the side frame members of the casing of a window or like building opening when retracted, or extended across such opening between the frame members thereof. While hereinafter reference is directed primarily to a blind which includes a single slat series traversable from one side frame member of a casing toward the other, this invention is equally well suited for use in conjunction with a blind in which two separate slat series are extensible towards each other from opposite side frame members of such a casing.

Contrary to the constructions employed with many presently available types of vertical blinds, the subject blind does not require or employ a bottom guide track member for the lower extremities of the individual slats. Such bottom guide tracks are generally undesirable because of the unattractive appearance presented thereby, particularly when the blind is in the retracted position, and because of the cleanliness problem presented thereby in that accumulation of dust and dirt in and around such a track is difficult to prevent even by the most fastidious housekeeper or janitor. Heretofore such bottom tracks were widely employed to impart stability and resistance to sway to vertical blinds when extended. With the subject invention, slat stability is provided by the positioning means described in detail hereinafter.

2

Furthermore, contrary to the constructions employed with many presently available types of vertical blinds, the subject blind does not employ complicated overhead traverse cord and slat rotating mechanisms. Such mechanisms are unnecessary in the subject blind because traverse movement and slat orientation is effected upon actuation of the slat positioning means hereof by the first slat of the series in a predetermined manner. The slat positioning means limits to a predetermined number the various angular orientations in which the respective slats may be located when extended, and insures that a preselected angular orientation imparted to the slats is positively maintained so long as the slats remain in the extended position. The positioning means precludes alteration or modification of the angular orientation in which the slat series is located when extended. To modify such angular orientation it is necessary to first return the slat series to a retracted position, then selected a different angular orientation while the slats are retracted, and then retraverse the slats to the extended position to produce the modified angular orientation selected.

The angular orientation desired for the slat series is preselected while the slat series is in the retracted position by rotating the first slat of the series about its vertical axis to the orientation desired for the slat series, and by then moving the first slat toward the extended position. The positioning means which interconnects the respective slats of the series responds to the angular orientation and traverse movement imparted to the first slat to automatically and sequentially position all successive slats of the series in the preselected angular orientation chosen. All successive slats of the series follow in step-by-step sequential fashion from the retracted position to the extended position in response to traverse movement of the first slat. In this regard, in a blind which employs a single series of slats as shown in the attached drawings, the first slat of the series may be the slat which defines either the left hand margin or the right hand margin of the slat series because the slats of such a blind may be traversed either from right to left, or left to right, in the building opening in which the blind is mounted.

While the blind of this invention has been designed to permit location of its slats in only a limited number of predetermined angular orientations when extended, such angular orientations have been selected to meet the most common requirements for a vertical Venetian blind. In this regard, in one embodiment illustrated herein one such orientation permits the slats when extended to be fully closed so that edges of adjacent slats partially overlap to thereby restrict passage of most light and all vision therebetween; another angular orientation permits the slats when extended to be only partially closed so that edges of adjacent slats are free of overlap so that light passage and vision through the slat series is only partially restricted, yet so that direct sunlight and glare may be precluded. Another embodiment illustrated herein permits a third angular orientation in which the slats when extended are fully opened so that vision and light travel therebetween is substantially unobstructed.

In this connection, while the embodiments of the positioning means employed with the blinds illustrated herein permit only two predetermined angular orientations or three predetermined angular orientations, depending upon the construction of the positioning means chosen, it is within the purview of this invention that slat series positionable in more than three predetermined angular orientations may be provided upon modification of the positioning means disclosed herein within the scope of this invention. However, in that event, the number of angular orientations permitted will still be predetermined in accordance with the particular construction of the positioning means of this invention, rather than by the use of

complex slat rotating mechanisms of the type heretofore employed which permit slat orientation in an infinite number of positions. Such slat rotating mechanisms are not desired or included in this invention because of their complex nature and relatively high expense when compared with the simple positioning means of this invention.

Complex and expensive slat rotating mechanisms of the type known heretofore which permit unlimited numbers of angular slat orientations have been found unnecessary because the limited number of predetermined angular orientations permitted by the positioning means of this invention is adequate to meet all light and vision problems to which vertical Venetian blinds normally are subjected. Also, the subject positioning means maintains the slats securely in the angular orientation chosen so that slat chatter and lateral sway when the slats are extended is substantially if not completely eliminated.

Maintenance of the predetermined orientation selected for the slats is accomplished by interconnecting linkage structures of the positioning means, as described herein-after in detail, which permit traverse movement of adjacent slats toward and away from each other but which brace such adjacent slats against rotative movement relative to each other when the slats are moved to the extended position. This bracing effect is produced by such interconnecting linkage structures which cooperate with each other to define a generally rigid assembly when the series of slats is extended, as described more fully herein-after with respect to the various species of the invention disclosed herein.

From the foregoing it should be understood that objects of this invention include the provision of an improved simple and inexpensive vertical Venetian blind; the provision of a vertical Venetian blind which includes means for positively positioning the slats thereof in a preselected one of a number of predetermined angular orientations when the slats are traversed to an extended position in a window or like building opening; the provision of a vertical Venetian blind which eliminates complex overhead traverse cord and slat rotating mechanisms from its construction; the provision of a vertical Venetian blind in which a series of blind slats is actuated in positive step-by-step chain reaction fashion in response to manual actuation of a first slat of the series; the provision of a vertical Venetian blind in which the angular orientation of the blind slats when in the extended position is determined at the time the slats series is in the retracted position in accordance with the angular orientation imparted to the first slat of the series as traverse movement is initiated; and the provision of a method of traversing slats of a Venetian blind construction while simultaneously locating the respective slats in a preselected one of a limited number of predetermined angular orientations.

These and other objects of this invention will become apparent to one skilled in the art from a study of the following description, reference being directed to the accompanying drawings in which several embodiments of the invention are illustrated.

FIG. 1 is a front elevational view of a vertical Venetian blind embodying the subject invention mounted in and traversed across a window opening to its extended position with the slats thereof in the fully closed orientation.

FIG. 2 is a front elevational view similar to FIG. 1 showing the slat series in a retracted position compacted against one side frame member portion of the casing of the window opening.

FIG. 3 is a vertical sectional view taken in the plane of line 3—3 of FIG. 2 showing details of the supporting means employed for mounting the blind slats for traverse movement in the window opening.

FIG. 4 is a vertical sectional view taken in the plane of line 4—4 of FIG. 3 showing further details of the slat supporting means.

FIGS. 5, 6 and 7 are generally schematic top plan views of the series of blind slats showing various predetermined

angular orientations in which the slats are locatable when in the extended position.

FIG. 8 is a horizontal sectional view taken in the plane of line 8—8 of FIG. 2 illustrating details of a first embodiment of the blind construction shown in the retracted position.

FIG. 9 is a vertical sectional view taken in the plane of line 9—9 of FIG. 8 illustrating details of the positioning means employed in the first embodiment.

FIG. 10 is a horizontal sectional view taken in the plane of line 10—10 of FIG. 1 showing details of the first embodiment when the same is in the extended position with the slats thereof in the fully closed orientation.

FIG. 11 is a horizontal sectional view corresponding generally to FIG. 10 but showing the slats of the blind in the partially closed orientation.

FIG. 12 is a front elevational view of the first embodiment showing the slats in the partially closed orientation of FIG. 11.

FIG. 13 is a horizontal sectional view of a second embodiment of the blind construction showing the same in the retracted position.

FIG. 14 is a vertical sectional view of the second embodiment taken in the plane of line 14—14 of FIG. 13.

FIG. 15 is a horizontal sectional view of the second embodiment showing the same in the fully extended position with the slats in a fully opened orientation.

FIG. 16 is a vertical sectional view of the second embodiment taken in the plane of line 16—16 of FIG. 15.

FIGS. 17 and 18 are horizontal sectional and cut-away elevational views, respectively, of the second embodiment showing the same in the extended position with the slats in a partially closed orientation.

FIG. 19 is a horizontal sectional view of the second embodiment showing the same in the extended position with the slats in a fully closed orientation.

FIG. 20 is a horizontal sectional view of a third embodiment of the blind construction showing the same in the extended position with the slats thereof in the fully opened orientation.

FIG. 21 is a vertical sectional view of the third embodiment taken in the plane of line 21—21 of FIG. 20.

FIG. 22 is a plan view of a portion of the slat positioning means employed in the third embodiment.

FIG. 23 is a vertical sectional view through the portion of the slat positioning means taken in the plane of line 23—23 of FIG. 22.

FIG. 24 is a vertical sectional view corresponding generally to FIG. 21 but showing the third embodiment in the fully retracted position.

FIG. 25 is a horizontal sectional view of the third embodiment showing the same in the extended position with the slats in a partially closed orientation.

FIG. 26 is a horizontal sectional view corresponding generally to FIG. 25 showing the slats of the third embodiment in a fully closed orientation.

FIG. 27 is a horizontal sectional view of a fourth embodiment of the blind construction showing the same in the extended position with the slats thereof in a fully opened orientation.

FIG. 28 is a vertical sectional view of the fourth embodiment taken in the plane of line 28—28 of FIG. 27.

FIG. 29 is a sectional view of a portion of the slat positioning means employed in the fourth embodiment taken in the plane of line 29—29 of FIG. 28.

FIG. 30 is a horizontal sectional view of the fourth embodiment showing the same in a retracted position.

FIG. 31 is a vertical sectional view of the fourth embodiment taken in the plane of line 31—31 of FIG. 30.

FIG. 32 is a horizontal sectional view of the fourth embodiment showing the same in the extended position with the slats thereof in a partially closed orientation.

FIG. 33 is a horizontal sectional view corresponding generally to FIG. 32 but showing the slats in a fully closed orientation.

Before describing details of construction of the various embodiments of this invention illustrated in the accompanying drawings, reference is first directed to FIGS. 5, 6 and 7. The series of slats 1 of the subject Venetian blind construction are designed to be actuated manually during traverse movement by grasping and moving the first slats 1' of the series from the retracted position shown in FIG. 2 to the extended position shown in FIG. 1, and vice versa. As will be described hereinafter, the angular orientation desired for the respective slats of the series when extended is determined at the time the slats are in the retracted position in accordance with the angular orientation imparted to the first slat 1' when traverse movement is initiated. Only a predetermined number of orientations is permitted in accordance with the construction of the positioning means employed with a given series of slats.

The positioning means actuates and locates the respective slats in successive step-by-step chain reaction fashion in direct accord with the angular orientation preselected and imparted to the first slat of the series when in the retracted position and in response to movement of the first slat to the extended position. Thus, if it is desired to have the slats oriented in the fully closed position when extended (that is, with the planes of the slats extending generally parallel to the transverse window axis along which the slat series is movable during traverse movement, see FIG. 5) the longitudinal edge of the first slat indicated by the arrow in FIG. 5 is grasped and pulled. This orients such first slat in the fully closed orientation and all successive slats are automatically oriented in a corresponding orientation by the slat positioning means as seen in FIG. 5 when the first slat is traversed.

If it is desired to orient the slats in a partially closed position (that is, with the planes of the slats extending at a predetermined angle, such as 45°, relative to the transverse window axis along which the slats are traversable, see FIG. 7), the opposite longitudinal edge of the first slat indicated by the arrow in FIG. 7 is grasped and pulled. This orients the first slat in the partially closed orientation which results in the positioning means automatically locating each of the successive slats in a corresponding orientation.

In those embodiments of blind construction which permit a fully opened slat orientation (that is, with the planes of the slats extending generally normal to the transverse window axis, see FIG. 6), the first slat of the series when traversed is maintained generally in the same orientation in which the slats are located when in the retracted position. That is, as seen in FIGS. 5, 6, and 7, when the slats are retracted their planes extend generally normal to the plane of the transverse window axis. By maintaining that orientation in the first slat when the same is traversed, as seen in FIG. 7 each succeeding slat follows in similar orientation and is retained therein by the slat positioning means.

Thus, it should be understood that if the user of the blind construction desires to completely close off a window opening, he grasps and pulls one edge of the first slat of the series to the extended position; if he desires to only partially close off a window opening, he grasps and pulls the other edge of the first slat; if he desires to locate the blind in the extended position without closing off the window opening to any appreciable degree, he grasps the first slat and retains its orientation when retracted during traverse movement thereof to the extended position.

It is an important feature of this invention that when the slat series is located in a given preselected angular orientation when extended, such preselected orientation is positively maintained by the slat positioning means so long as the slat series remains in the extended position. That is, the positioning means, which may take various and varied forms as disclosed hereinafter, includes a series of interconnecting linkage structures which are interposed

between adjacent pairs of slats of the blind and operatively interconnect the same. Such structures are designed to permit relatively free movement of adjacent slats toward and away from each other in a traverse direction of movement. However, such structures are designed to positively preclude relative rotation between adjacent slats when such slats are moved to the extended position. Such rotation prevention is accomplished by the linkage structures cooperating with the respective slats between which they are interposed to provide a generally rigid brace which effectively locks together such adjacent slats. Rotation prevention is further enhanced because all slats of the series are similarly braced against rotation when the slat is extended, thereby to cooperate with each other in defining a generally rigid interconnected assembly. To modify the angular orientation of the slat series of the subject blind construction when extended it is first necessary to return the slat series to a retracted position, then to reorient the first slats of a series in a different desired orientation, and then again traverse the slat series to the extended position. The slat positioning means also minimizes or eliminates slat chatter and lateral sway when the slat series is subjected to air currents when in the extended position. The exact manner in which the positioning means performs its intended slat orienting and bracing functions is described with respect to, and will become evident from a study of, each of the detailed disclosures of the respective species of this invention discussed hereinafter.

Reference is now directed to FIGS. 3 and 4, taken in conjunction with FIGS. 1 and 2, which illustrate one embodiment of means which may be employed for supporting the blind for traverse movement in a building opening, such as a window opening 2 defined by a rectangular window casing 3 of any conventional construction. Extending across the top frame member of the window casing as seen in FIG. 3 is a decorative valance 4 between the opposite side rails 6 of which is mounted a supporting track 7 which extends the full transverse distance across the window opening. Screws 8 located at spaced positions along the length of the track secure the track firmly in place. The longitudinal axis of track 7 defines the transverse axis of the window opening along which the respective slats of the blind construction are moved when traversed. It is this transverse axis which provides a plane of reference to which the angular orientation of the respective slats is related when the slats are in the extended position as mentioned previously.

Each slat of the series is supported in the track 7 by a supporting slide or roller member 9 movably received in the track. Depending from each supporting member 9 is a pivot pin 11 which secures an angled mounting bracket 12 to the supporting member. Each mounting bracket 12 in turn is secured by a suitable connecting pin 13 to an associated slat via an opening in the slat provided in line with the slat axis closely adjacent the top thereof. Thus, each slat of the blind series is securely supported for traverse movement in response to actuation of the first slat of the series yet each such slat may pivot about its axis on its associated pivot pin 11 to the preselected angular orientation chosen therefor in accordance with the manner of movement of the first slat of the series. The various components of the slat supporting means just described may be formed from suitable plastics or metals commonly employed in Venetian blind constructions.

Because Venetian blind slats commonly are made from relatively thin and generally flexible material, such as sheet metal or plastic, preferably the first slat 1' of the series is provided with means to facilitate grasping thereof during traverse movement. Such grasping means in the illustrated embodiment comprises an elongated handle structure, generally designated 16, extending along each longitudinal edge of the first slat, preferably for the full length thereof as best seen in FIGS. 1 and 5-7.

Each handle structure 16 straddles its associated longitudinal slat edge and is secured along such edge by a series of headed pins 17 which extend through the opposing portions of the handle and through the associated slat adjacent its edge. The material from which the handles are formed preferably is of the same metal or plastic material from which the slats are formed so that the handles blend in with the slat series and are generally harmonious with the overall appearance of the blind. The handles, in addition to providing means to facilitate grasping of the first slat of the series, strengthen and reinforce the first slat and impart additional rigidity thereto to resist stresses applied thereto during traverse movement of the blind.

As seen in FIG. 1, the first 1' at each of the opposite ends of the slat series is provided with graspable handles 16 because the slat series shown in such figure may be traversed from right to left, or from left to right, as may be desired. In this regard, although not necessary, releasable means (not shown) may be provided in conjunction with each of the opposite side frame members 3' of window casing 3 to maintain an adjacent first slat of the series attached to such side frame member when the blind is traversed with its opposing first slat leading.

The graspable handle structures 16 have been illustrated in the drawings only in conjunction with a first embodiment of the blind shown in FIGS. 8-12. It should be understood, however, that similar constructions preferably are employed in conjunction with the other embodiments illustrated also.

In the blind embodiments to be described, only several adjacent slats and portions of the positioning means cooperating therewith have been illustrated for purposes of clarity. But it should be understood that the positioning means employed with each blind embodiment is located between and interconnects each adjacent pair of slats of the entire series. Similarly, in FIG. 1, positioning means been been illustrated in two runs adjacent the upper and lower ends of the slats. Depending upon the size of the blind only one run adjacent the lower ends of the slats may suffice, or more than two runs of positioning means may be required.

Reference is now directed to the first blind embodiment shown in FIGS. 8-12. The positioning means which interconnects adjacent slats of this embodiment and which insures and maintains location of the respective slats in a preselected angular orientation in response to traverse movement of the first slat of the series comprises a series of link structures which are mounted between the respective adjacent slats of the series. Each link structure includes a movable linkage which is connected by mounting structure with the respective slats of an associated pair of slats between which such linkage is positioned.

The linkage comprises, as seen in FIGS. 9, 11 and 12, a pair of scissors links 21 and 22 respectively. These links are overlapped adjacent one of their ends and are pivotally interconnected with each other by means of a headed pin 23 which projects from link 21 through an opening provided in link 22. To limit the angle at which the links may extend relative to each other when the slat series is in the fully extended position, stop means in the form of a projecting shoulder 24 is provided on link 22. Shoulder 24 engages a marginal edge of link 21 (as seen in FIGS. 10, 11 and 12) when the slats are in either of their predetermined angular orientations when in the fully extended position. It should be understood that stop shoulder 24 does not interfere with pivotal movement of link 22 relative to link 21 in either the clockwise or counter-clockwise direction from the position seen in FIG. 9 so that the slats may be readily positioned in either of the extended positions shown in FIG. 10 or 11. It is stop shoulder 24 which limits the distance adjacent slats of the series may be spaced from each other in accordance with the predetermined dimensions of the slats of the series. As it is seen in FIGS. 10 and 11, when links 21 and 22

are extended when the slats between which they are positioned are extended, such links cooperate with each other to define, in effect, a single rigid link or brace.

It should be noted that the links 21 and 22 are mounted between adjacent slats in inverted V fashion. Thus the weight of the links assists in maintaining the slats spaced from each other in the angular orientation selected. This link mounting arrangement thereby resists unintentional movement of individual slats toward the retracted position.

At their lower ends, each of the links 21 and 22 is movably connected with an associated slat by mounting structure provided for that purpose. In the embodiment illustrated, such mounting structure comprises slotted tabs 26 and 27 struck directly from the slats in spaced vertical relationship as best seen in FIGS. 11 and 12. All slats except the first slat of the series include two such tabs provided generally along the longitudinal axes thereof which project in opposite directions therefrom. The first slat of the series requires only one such tab.

At their lower ends, each of the links 21 and 22 is movably connected with an associated slat by mounting structure provided for that purpose. In the embodiment illustrated, such mounting structure comprises slotted tabs 26 and 27 struck directly from the slats in spaced vertical relationship as best seen in FIGS. 11 and 12. All slats except the first slat of the series include two such tabs provided generally along the longitudinal axes thereof which project in opposite directions therefrom. The first slat of the series requires only one such tab.

Tabs 26 all are struck to extend in one direction from the slats, while tabs 27 all are struck to extend in an opposite direction therefrom. The linkage defined by links 21 and 22 extends between each adjacent vertically aligned pair of tabs 26 and 27 of adjacent slats. As seen in FIG. 12, tabs 26 and 27 of each slat are vertically staggered relative to each other so that the linkages between adjacent pairs of slats may be aligned with each other when the slats are in the retracted position shown in FIG. 8. In this regard, each pair of tabs 26 and 27 cooperate to receive a linkage therebetween in compact relationship so that the slat series when retracted may form an extremely compact pack as seen in FIG. 2.

Each of links 21 and 22 is secured to its associated tab by means of a headed pivot pin 28 which extends through an aperture provided in the end of the link and through an elongated slot 29 provided in the associated tab. The links and connecting pins employed therewith may be formed from any suitable material, such as a rigid sturdy plastic or a relatively light weight metal such as aluminum.

Tabs 26 and 27 as seen in FIGS. 10 and 11 extend from their associated slats at a predetermined angle relative to the plane thereof. Such tabs thereby define angular guide members which cooperate with an associated linkage in positively establishing the angular relationship between such linkage when extended and each pair of slats interconnected thereby. It is the angle at which the tabs project which determines the angular orientation of the respective slats relative to the transverse axis of the window opening when the slats are extended to the partially closed orientation shown in FIG. 11. In such orientation, the slats extend generally at a 45° angle relative to the transverse axis of the window opening because the tabs extend generally at a 45° angle relative to the plane of their associated slat.

When the slats are in the fully closed orientation of FIG. 10, it will be noted that the linkage between adjacent slats lies generally parallel to the plane of the slats, thereby permitting the edges of adjacent slats to overlap to provide the fully closed orientation desired. Such overlapping is permitted by the fact that the ends of the slots 29 in which the heads of pins 28 are slidable terminate generally in the plane of the respective slats. Thus the slats in the fully closed orientation shown lie generally parallel to the plane of the transverse axis of the window opening.

In this regard, it should be noted that the linkage interconnecting each pair of slats lies generally in line with the transverse window axis when the slats are fully extended as shown in FIGS. 10 and 11. The respective linkages and tabs restrict movement of the slats from the extended orientation shown because of the interconnection of adjacent slats with each other by such linkages. Thus to change the angular orientation, it is first necessary to re-

turn the slats to a retracted position as previously mentioned.

Rotation of the individual slats while the slat series is in either of the predetermined angular orientations shown in FIGS. 10 and 11 is prevented by cooperation of the linkages between adjacent slats. As noted previously, when the linkages are in the extended position they define a series of generally rigid braces all of which lie generally in line with each other, as seen in FIG. 11. Thus, rotation of an individual slat is positively resisted by the slats on opposite sides thereof which are operatively interconnected therewith.

Relative rotation is resisted even between two slats by the engagement of the links with the outer surfaces of the respective tabs 26 and 27 (FIG. 11) or with the surfaces of the slats themselves (FIG. 10). Even when a given slat is collapsed, by traverse movement, against its neighboring slat, rotation is still resisted until all slats are collapsed together, at which time the series of slats may be rotated, at least to some extent, generally in unison as a group. By manufacturing the components of the respective linkage structures to close tolerances, even slight relative rotation between adjacent slats when the slats are in the extended position may be obviated.

It should be understood that the angle at which the slats extend relative to the transverse window axis when in the partially closed orientation (FIGS. 11 and 12) may vary depending upon the angle imparted to the tabs with respect to the planes of the slats. That is, if it is desired that the slats when fully extended and located in the partially closed orientation should have an angular orientation different from the 45° orientation shown in the drawings, the tabs 26 and 27 need only be formed when the blind is manufactured to extend at some other acute angle desired relative to the plane of their respective slats.

Considering the first blind embodiment shown in FIGS. 8-12 in conjunction with the schematic showings of FIGS. 5 and 7, it should be understood that location of the slats in the extended partially closed orientation shown in FIGS. 11 and 12, in which adjacent edges of adjacent slats are spaced from each other, may be obtained merely by grasping and pulling on one longitudinal edge of the first slat 1' in the direction of the arrow seen in FIG. 7. This action automatically rotates the first slat about its axis toward the orientation desired. Such rotation of the first slat initiates rotation of all other slats of the series because all slats when in the retracted position are grouped together in a compact pack, as seen in FIG. 8. Thus, when traverse movement of the first slat of the series is initiated, the remaining slats of the series have already been rotated, at least to some extent, toward the orientation selected therefor. It is this initial partial rotation of the slats toward the desired orientation which initiates and insures the chain reaction of the linkage structures on the respective slats of the series. Because the linkages permit the slats to be located in only a generally parallel relationship relative to each other, proper orientation is insured by the linkages in step-by-step fashion as each successive slat is moved toward its extended position. That is, upon, traverse movement of the first slat, the successive slats are traversed and fully rotated automatically by the linkages and mounting tabs in succession to sequentially locate each slat in the orientation predetermined by the angle of projection of the tabs. In this regard, it should be noted that the pins 28 which pivotally connect each link with a tab have traveled to the outer ends of the slots 29 in the respective tabs so that the links lie flush against the outer guide surfaces of their associated tabs. See FIGS. 11 and 12.

If it is desired to position the slats in the fully closed angular orientation shown in FIG. 10, it is merely necessary to grasp and pull the opposite longitudinal edge of the first slat 1' of the series in the direction of the arrow seen in FIG. 5. This action automatically produces at least partial rotation of all slats toward the fully closed orientation desired so that subsequent traverse movement

of the first slat produces a chain reaction similar to but generally opposite from that described previously with respect to FIGS. 11 and 12. In this regard, as the first slat is rotated in the opposite direction about its vertical axis, it thereby causes rotation of the successive slats, which rotation draws the links of successive slats away from their associated mounting tabs. This results in the pivot pins 28 traveling to the inner ends of the tab slots 29 so that the links when extended may lie generally in the same plane as the planes of the slats. Thus the slats may be oriented to lie generally parallel to the transverse window axis so that the edges of adjacent slats may overlap as seen in FIG. 10.

As noted previously, once the slats are positioned in either of the preselected angular orientations described when fully extended, rotation of the slats in unison, or individually, is positively precluded because the linkages between all slats work together to define, in effect, an operatively continuous series of braces all of which are effectively tied together in a single operative assembly. Thus, to change the orientation of the slat series, or any individual slat, it is first necessary to collapse the slat series to the retracted position, in which position it is possible to rotate the slats as a group, as described previously by altering the orientation of the first slat of the series.

Because the link structures of the positioning means shown in the FIGS. 8-12 embodiment of this invention permits movement in only two directions, that embodiment of the blind construction is capable of only the two position angular orientation shown in FIGS. 5 and 7, namely the fully closed orientation and the partially closed orientation of about 45° or some other suitable preselected angle.

The other embodiments of this invention described hereinafter employ positioning means which permits at least one additional predetermined angular orientations when the slat series is fully extended, namely the fully opened orientation shown schematically in FIG. 6 in which each slat extends generally normal to the transverse axis of the window opening. This third orientation is obtainable because of modified details of construction in the link structures employed in the other embodiments.

Referring now to FIGS. 13 through 19, a second embodiment of the blind construction is shown in which the slats may be located in three predetermined angular orientations when in the extended position.

Each of the series of link structures of the second embodiment includes a linkage defined by a single link 36 having a predetermined angle of longitudinal twist imparted thereto, as perhaps best seen in FIGS. 16, 17 and 19. Link 36 has a longitudinal slot 37 formed therein which extends for the major portion of the length thereof and which is cooperable with the mounting structure which secures the link to one of the slats of the adjacent pair of slats between which the link is positioned as will be described.

At one end 38 thereof link 36 is provided with mounting structure defined by a bent margin 39 which extends through a circular aperture 41 provided in an associated slat. Thus, the link is pivotally connected at one of its ends so such slat but is precluded from separation therefrom by the bent margin 39 located on one side of the slat and a pair of stop shoulders 42 located on the opposite side of the slat. The bent margin 39 and shoulders 42 have a reduced dimension connecting neck 43 located therebetween which is located in the slat opening 41.

Link 36 is connected with the other slat of the pair of slats between which it is positioned by other mounting structure comprising an angular guide member 44 defined by a generally L shaped body when viewed in vertical section (note FIG. 14). One leg 45 of the guide member is provided with a tab portion 46 which is received through an aperture 47 in the associated slat. Tab portion 46 defines one end of a reduced neck portion 48 by means of which the tab portion is connected with the main portion 75 of leg 45 of the angular guide member. Limited hinge type

movement is permitted between the guide member and its associated slat in the manner noted by comparing FIGS. 14 and 16. The other leg 51 of the angular guide member has a headed mounting pin 49 projecting therefrom into and through the slot 37 provided in link 36. Thus, link 36 is slidably movable relative to the angular guide member yet is precluded from separation therefrom by the headed pin 49.

As perhaps best seen in FIG. 17, leg 51 from which the mounting button 49 projects defines an angular guide surface which extends at a predetermined angle relative to the plane of the slat to which the guide member 44 is attached. It is this angular guide surface which establishes the predetermined partially closed angular orientation of the slat series when the slats are located in the extended position. In the embodiment illustrated, approximately a 45° angle is defined by the guide surface relative to its associated slat.

As with the first embodiment of this invention described previously, referring to FIGS. 5 and 19, if it is desired to locate the slats in the fully closed orientation when the slat series is extended, one edge of the first slat 1' is grasped, rotated and pulled in the direction of the arrow in FIG. 5. This initial rotation of the first slat causes partial initial rotation of all slats of the series toward the orientation desired. This initial change in orientation results in each successive slat being fully rotated and traversed in sequence in accordance with continued rotation and traversal of the first slat with the respective links 36 sliding over their respective mounting pins 49 until each pin in sequence reaches the end of its associated slot 37 as shown in FIG. 19. To obtain this condition, referring to FIG. 13 wherein the slats are shown in the retracted position, the edge of slat 1' lying towards the bottom of that figure is grasped and traversed as described. As noted in FIG. 19, the longitudinal twist in each link 36 counteracts the angle imparted to the guide surface of leg 51 of the guide member so that edges of adjacent slats may be moved into close overlapping relationship characteristic of the fully closed orientation.

Referring to FIGS. 7, 14 and 16, when it is desired to locate the slats in the partially closed orientation the opposite edge of the first slat 1' of the series, namely the edge lying at the top of FIG. 13, is grasped and pulled. This rotates the first slat in an opposite direction from that described above and causes partial rotation of all slats of the series so that each succeeding slat will be fully rotated and traversed in sequence in direct response to actuation of the first slat. However, in this connection, the angled guide surface of leg 51 of each angular guide member 44 positively limits the angle at which a link 36 may extend relative to the guide member and thereby automatically positions such link to in turn determine the angular orientation of its associated slats as seen in FIGS. 17 and 18.

Referring now to FIGS. 13 through 16, the connecting means of this second embodiment also permits the slats to be oriented in a third angular orientation, namely one in which the respective slats extend generally normal to the transverse axis of the window opening as seen in FIG. 6. Such angular orientation is obtained merely by withdrawing the first slat 1' of the series from the retracted position while maintaining the orientation which such first slat has when in the retracted position. In this regard, when the slat series is retracted, each slat thereof extends generally normal to the transverse window opening axis as seen in FIG. 13. As seen in FIG. 6, if this normal position is maintained during initial traverse movement of first slat 1', each succeeding slat will be similarly oriented. The longitudinal twist imparted to each link also comes into play in this angular orientation in that it counteracts the angle of the guide surface of leg 51 of the mounting guide member 44 so that the successive links may be positioned to extend generally normal relative to the planes of its associated slats as seen

in FIG. 15. The longitudinal twist imparted to the link prevents binding of the link on the mounting pin 49 of the angled guide member 44 which would result in the absence of such twist, thereby insuring smooth traverse movement of the slats between the retracted and extended positions. It should be understood that the components of the positioning means are connected with each other with sufficient looseness to permit easy and smooth traverse movement of the slats and yet with sufficient tightness to preclude unnecessary play and chatter therebetween.

A third embodiment of this invention is illustrated in FIGS. 20 through 26. This embodiment also permits three predetermined angular orientations of the slats when in the extended position. The positioning means of this embodiment comprises a series of link structures each of which includes a linkage defined by a single link 60 which has oppositely directed bent shoulders 61 and 62 at opposite ends thereof as best seen in FIG. 21. These shoulders limit the amount of longitudinal movement of link 60 relative to the mounting structures of the positioning means by which the link is movably connected with the pair of slats between which it is located. Each mounting structure, as seen in FIG. 22, comprises a crescent shaped angular guide member 63 having a semicircular cut out 65 therein. The guide members which secure each link between a pair of slats are identical in construction but are oppositely oriented on the respective slats as best seen in FIGS. 20 and 25.

Each guide member 63 is formed from a generally circular single piece of sheet metal or plastic, having a circular hole therein, which is folded upon itself along a fold line 64 (FIG. 22) to form a two ply member having a slot 66 between the plies thereof (FIG. 23) through which an associated end of link 60 extends and in which such link end is slidable. The angular guide member is provided with a stop shoulder 67 spaced inwardly from one end thereof which closes off slot 66 of the guide member along one edge thereof. Thus, as shown in dotted lines to the left of FIG. 22, when link 60 strikes shoulder 67 further movement of the link, and a slat associated therewith, is positively restricted. However, slot 66 at the other end of the guide member is not provided with such a stop shoulder so that the link may move fully around the slot to the dotted line position shown to the right of FIG. 22.

Each angular guide member 63 of the mounting means is provided with a pair of opposed notches 68 adjacent fold line 64 which define reduced dimensioned neck portions, which provide shoulders 69, received through appropriately spaced openings 71 in a slat as perhaps best seen in FIG. 25.

Referring now to FIG. 24, when the slat series is in the retracted position, each link 60 moves within each of its associated angular guide members 63 to the retracted position shown, namely the dotted line position shown in the middle of FIG. 22. However, when it is desired to position the slats in the fully open orientation in the extended position, it is merely necessary to maintain the first slat 1' of the series normal to the transverse axis of the window opening in which the slat series is mounted so that each link 60 slides within its associated angular guide members 63 until the respective stop shoulders 61 and 62 engage the inner periphery of the cut out 65 of the guide members, as shown in the solid line position in FIG. 22. Preferably the opposing plies of the mounting guide members exert sufficient frictional force on the links 60, without interfering with smooth blind traverse motion, so that the links are maintained in the position selected therefor.

When it is desired to locate the slat series in the fully closed orientation shown in FIG. 26 it is merely necessary to grasp the longitudinal edge of the first slat of the series indicated by the arrow of FIG. 5 and to move such first slat to the fully extended position. Succeeding

slats will rotate and follow in chain reaction fashion as described with respect to the previously described embodiments. Because the stop shoulders 67 provided on the respective guide members 63 do not come in contact with the links 60 when the first slat of the series is thus withdrawn, the slats may assume the fully closed orientation shown in FIG. 26.

If it is desired to locate the slats in the partially closed orientation as shown in FIG. 25, the opposite longitudinal edge of the first slat of the series is grasped and pulled, as shown schematically in FIG. 7. The other slats rotate and follow in chain reaction fashion until the orientation of FIG. 25 is achieved. In this regard, when the first slat of a series is thus actuated, the respective links 60 contact the associated stop shoulders 67 provided on the respective angular guide members 63 associated therewith to positively limit the degree of rotation of successive slats about their vertical axes and to thereby automatically position all the slats in the predetermined partially closed angular orientation shown in FIG. 25. Depending upon the location of the stop shoulder 67, any predetermined angular orientation desired may be obtained. In the embodiment illustrated herein, an orientation of approximately 45° relative to the transverse window axis is obtained, as seen in FIG. 25.

A fourth embodiment of the invention is shown in FIGS. 27 through 33. This embodiment is also a three orientation embodiment as seen from FIGS. 27, 32 and 33 respectively. The positioning means of this embodiment comprises a linkage which includes a single link 76 interposed between each pair of adjacent slats and secured therebetween by mounting structures. Each link 76 at a lower end thereof is secured to a slat by means of a headed pivot pin 77 extending through a slat opening 78. A short slot 79 is provided adjacent the link lower end through which pin 77 also extends. The short slot 79 permits relative pivotal and limited longitudinal movement between link 76 and the pin 78.

At its upper end link 76 is secured to the other slat of the pair of slats between which it is interposed by mounting structure defined by an angular guide member 81, which in the embodiment illustrated comprises a one piece plastic button having disposed centrally thereof a headed projecting pin 82 which extends through an aperture 83 provided therefor in the slat. Preferably the aperture 83 is polygonal in cross section and the pin 82 is correspondingly contoured with a polygonal neck to preclude rotation of the button relative to the slat.

The angular guide member 81 has another headed pin 84 (FIG. 28) projecting therefrom in an opposite direction in line with the pin 82 just mentioned. Pin 84 is received through an elongated slot 86 adjacent the upper end of link 76. Thus, substantial relative longitudinal movement is permitted between the link and its latter mentioned associated slat, limited only by the longitudinal extent of the slot 86.

It should be noted that at each of its lower and upper ends, 87 and 88 respectively, link 76 is provided with a curved portion which extends at approximately a 45° angle relative to the plane of the intermediate portion of the link. Similarly the angular guide member 81 is provided with an angled guide surface 89 which extends generally at 45° relative to the plane of the slat associated therewith (FIG. 27).

When the slat series is traversed from the retracted position shown in FIGS. 30 and 31 to the extended position in which the slats are in the predetermined partially closed orientation shown in FIG. 32, the angled upper end 88 of link 76 is compatibly engaged with the angled guide surface 89 and the adjacent portion of guide member 81 to thereby locate the link in the preselected orientation determined by the angle of guide surface 89 relative to the plane of its associated slat. This orientation of each link automatically orients each slat connected with the lower end of such link. As seen in FIG. 29, along one

longitudinal edge of the link an upturned lip 90 is formed which permits link 76 to ride over the guide surface 89 of the guide member 81 without binding thereon.

When the slat series of this fourth embodiment is oriented in the fully closed orientation, as shown in FIG. 33, it will be noted that the bent portion at the link upper end 88 is generally free of engagement with the angular guide surface 89 of the guide member 81 so that the respective slats may be located in the fully closed overlapping orientation shown.

Finally, if it is desired to locate the respective slats in the fully opened orientation, as with embodiments earlier described, it is merely necessary to maintain the first slat of the series generally normal to the transverse axis of the window opening as the slats are withdrawn. This results in the mounting pins 78 and 84 riding in their associated slots 79 and 86 provided at opposite ends of each link to permit movement of the slats to the fully opened orientation shown in FIGS. 27 and 28. In this regard, the upper end 88 of each slat, as perhaps best seen in FIG. 28, is also provided with a right angled bent marginal shoulder 92 which engages with the upper edge of the angular guide member 81 to positively limit longitudinal movement between each link and the pin 84 of its associated angular guide member when the slats are moved to the fully opened orientation as seen in FIG. 28.

From the foregoing four embodiments illustrated and described, it should become apparent that modifications in the construction of the positioning means employed with a vertical Venetian blind embodying this invention may be devised. However, all such positioning means chosen should be capable of producing the same novel traverse function described herein, and of operating in the same novel traverse method disclosed herein, to automatically locate all slats of a series in a predetermined angular orientation, which is selected while the slats are in the retracted position and which is determined in accordance with the angular orientation imparted to the first slat of the series when traverse movement thereof is initiated. It should be understood that the positioning means chosen should be capable of performing the important function of restricting alteration of the angular orientation of the slat series so long as the slat series is retained in the extended position. This important function is accomplished by the respective slat structures of the positioning means cooperating with each other to preclude pivotal movement of individual slats except in sequence while the slats are moving between the retracted and extended positions.

Having thus made a full disclosure of this invention and several embodiments of the construction in which it may be formed, reference is directed to the appended claims for the scope to be afforded thereto.

I claim:

1. A method of traversing a series of slats of a traverse type vertical Venetian blind while simultaneously orienting said slats in sequence in a preselected one of a limited number of angular orientations relative to a reference plane, comprising the steps of providing positioning means which interconnect said slats and permit orientation thereof in only said limited number of angular orientations when said slats are traversed from a retracted position toward an extended position, said positioning means being sequentially responsive to actuation of the first slat of said series and to the angular orientation of said first slat during traverse movement, locating said first slat in a preselected orientation relative to said reference plane corresponding generally to a preselected one of said limited number of angular orientations in which it is desired to locate said slats when said slats are in said extended position, actuating said first slat to move the same toward said extended position, and while said first slat is moved toward said extended position sequentially and individually orienting successive slats of said series with said positioning means so that each of said successive slats of said series fol-

low in sequence in a corresponding orientation in response to step-by-step actuation of said positioning means by said first slat.

2. The method of claim 1 in which one preselected orientation of said series of slats is obtained by locating said first slat of said series with one of its edges in leading relationship when said series is in said retracted position, and then moving such slat toward said extended position with said one edge leading; and in which another preselected orientation of said slats is obtained by locating said first slat with the other of its edges in leading relationship when said series is in said retracted position, and then moving such slat toward said extended position with said other edge leading.

3. The method of claim 2 in which a third preselected orientation of said series of slats is obtained by locating said first slat of said series with neither of its edges leading when said series is in said retracted position, and then moving said first slat toward said extended position while maintaining such relationship between said edges thereof.

4. A method of traversing a series of operatively interconnected slats of a traverse type vertical Venetian blind to orient each of said slats in a preselected angular orientation relative to a reference plane along which said slats are traversable, comprising the steps of mounting said series of slats for traverse movement generally along said reference plane; locating the first slat of said series in an angular orientation relative to said reference plane which corresponds generally to said preselected orientation in which it is desired to locate said slats when said slats are in said extended position; when said first slat is thus oriented, actuating the same to move it toward said extended position; during such movement of said first slat, placing a restriction on the second slat of said series to preclude orientation thereof in an angular position relative to said reference plane which is substantially different from said preselected orientation; while said restriction is thus placed on said second slat, continuing movement of said first slat toward said extended position to thereby draw said second slat therewith; and sequentially placing a similar angular restriction on each successive slat of said series while continuing movement of said first slat, whereby all slats of said series may be located sequentially in said preselected

orientation in response to traverse movement of said first slat.

5. A method of traversing a series of operatively interconnected slats of a vertical Venetian blind to orient all said slats in a corresponding preselected angular orientation relative to a reference plane along which said slats are traversable, comprising the steps of mounting said series of slats for rotation about their respective vertical axes and for traverse movement generally along said reference plane; rotating the first slat of said series about its vertical axis to locate the same in an angular orientation relative to said reference plane which corresponds generally to said preselected orientation in which it is desired to locate said slats when said slats are in said extended position; when said first slat is thus oriented, moving the same toward said extended position; during such movement of said first slat, placing a restriction on the second slat of said series which precludes orientation thereof in an angular position which is substantially different from said preselected orientation but which permits rotation thereof to said preselected orientation during traverse movement thereof; while said restriction is maintained on said second slat, continuing movement of said first slat toward said extended position to thereby rotate said second slat about its vertical axis fully into said preselected orientation in accordance with the restriction placed thereon while the same moves toward said extended position; and sequentially placing a similar angular restriction upon each successive slat of said series while continuing movement of said first slat, whereby all slats of said series are rotated sequentially into said preselected orientation while the same are moved sequentially toward said extended position in response to traverse movement of said first slat.
